UNITED STATES PATENT OFFICE.

MARK BRAUN, OF PITTSBURGH, PENNSYLVANIA.

SPONGING APPARATUS.

1,044,437.

Specification of Letters Patent.

Patented Nov. 12, 1912.

Application filed May 18, 1912. Serial No. 698,308.

To all whom it may concern:

Be it known that I, MARK BRAUN, a citizen of the United States of America, residing at Pittsburgh, in the county of Allegheny and State of Pennsylvania, have invented certain new and useful Improvements in Sponging Apparatus, of which the following is a specification, reference being had therein to the accompanying drawing.

10 This invention relates to sponging apparatus for tailors, and my invention aims to provide:—First, a simple and inexpensive apparatus that can be advantageously employed by tailors and cleaners for economically and expeditiously sponging cloth or cloth in the form of garments. Second, a novel apparatus for subjecting cloth or garments to the action of steam that cleanses and dries a garment or prepares a piece of cloth whereby it can be made into a garment. Third, a sponging apparatus that obviates the necessity of a small customer depending upon a sponger in order to obtain cloth suitable for garments. Fourth, a 25 strong and durable apparatus of the above type that can be safely used for the purposes for which it is intended.

My invention further aims to accomplish the above results by an apparatus that permits of various kinds and forms of garments being sponged. The apparatus will be hereinafter specifically described and then claimed, and reference will now be had to the drawing, wherein is illustrated in 35 vertical section an apparatus in accordance with this invention.

A sponging apparatus in accordance with this invention embodies a boiler 1 in the form of a cylindrical receptacle made of 40 copper or other suitable material and provided with a rounded cover 2 that has a nipple 3 concentrically thereof. The cover 2 has a filling opening normally closed by a plug 4, and said receptacle is filled with 45 water, the quantity of water within the receptacle being determined by a water glass or gage 5 arranged at one side of the receptacle.

The nipple 3 has an integral transverse partition 6 constituting a valve body. The partition 6 has a recess 7 and vertically alining steam outlet openings 8 in communication with said recess and the boiler 1. The recess 7 is cylindrical and the walls

thereof are screw threaded, as at 9 for a 55 screw threaded valve stem 10 that has a head 11 and an opening 12, said opening adapted to register with the openings 8. The valve stem 10 is employed to control the passage of steam from the boiler through the openings 8.

The partition 6 has an angle port 13 and tapped into said port is an alarm or indicating device in the form of a valvular whistle 14 that serves as a blow-off or safety 65 valve. An excessive pressure of steam within the boiler 1 causes the valvular whistle 14 to produce a sound that will attract the attention of a tailor or other artisan and indicate that the apparatus is in condition 70 for sponging.

The nipple 3 has a steam outlet pipe 15 provided with a valve 16 and a hose or flexible connection 17, the purpose of which will hereinafter appear.

Screwed or otherwise mounted in the nipple 13 is a perforated sponging cylinder or foraminous body 18 that has a horizontal perforated partition 19 in proximity to the upper end thereof, said partition providing 80 a compartment 20 in the upper end of the cylinder.

Screwed in the upper end of the cylinder 18 is a cap or plug 21 that closes the compartment 20.

In operation a piece of cloth 22 is wound upon the sponging cylinder 18 and when the valve stem 10 is opened, the steam passes into the cylinder and through the perforations thereof, the steam sponging and thoroughly drying the cloth. Small pieces of 90 garments can be placed in the compartment 20 and steamed as though held by the exterior surface of the cylinder.

Any suitable burner or other source of 95 heat can be utilized for heating the contents of the boiler 1.

While in the drawing there is illustrated the preferred embodiment of the invention, it is to be understood that the structural elements are susceptible to such variations and modifications as fall within the scope of the appended claim.

What I claim is:—

A sponging apparatus comprising a boiler 105 provided with a vertically extending nipple, a transverse partition arranged within and integral with said nipple intermediate its

ends and provided with means for establishing communication between the upper and lower portions of the nipple, means mounted in said partition for closing communication between the upper and lower portions of the nipple, a vertically disposed perforated cylindrical member having its lower end extending and opening into the upper portion of said nipple, a perforated partition ar-

ranged within said member, and a cap for closing the upper end of said member.

In testimony whereof I affix my signature in the presence of two witnesses.

MARK BRAUN.
